UNITED STATES PATENT OFFICE.

JOHN JEPSON, OF WEST MERIDEN, CONNECTICUT, ASSIGNOR TO THE
MERIDEN BRITANNIA COMPANY, OF SAME PLACE.

DESIGN FOR SIRUP-CUP PLATE.

Specification forming part of Design No. **7,149**, dated February 3, 1874; application filed January 15, 1874.
[Term of Patent 7 years.]

To all whom it may concern:

Be it known that I, JOHN JEPSON, of West Meriden, in the county of New Haven and State of Connecticut, have invented a new Design for Sirup-Cup Plate; and I do hereby declare the following, when taken in connection with the accompanying drawings and the letters of reference marked thereon, to be a full, clear, and exact description of the same, and which said drawing constitutes part of this specification, and represents a side view of the cup on its plate.

This invention relates to a design for the plate used as a base for sirup-cups for table use; and the design consists in a plate made dishing to receive the cup and a bail attached to opposite edges of the plate and extending up over the cup, as shown in the accompanying drawings.

A is the plate, circular in shape and slightly dishing to form a seat for the cup; B, the bail attached to the plate upon opposite sides and extending up over the cup, as shown.

The cup itself is no part of this design, it only being necessary that a cup of some form be present to make a complete article.

I claim as my invention—

The design for sirup-cup plate, consisting of the plate A and bail B attached to the plate and extending up over the cup, as herein described, and shown in the accompanying illustration.

JOHN JEPSON.
